UNITED STATES PATENT OFFICE

111,473

DESIGN FOR A PORTABLE AIR CONDITIONER

Allan A. Feinberg, Minneapolis, Minn., assignor
to United States Air Conditioning Corporation,
Minneapolis, Minn., a corporation of Delaware

Application June 16, 1938, Serial No. 77,871

Term of patent 7 years

To all whom it may concern:

Be it known that I, Allan A. Feinberg, a citizen of the United States and a resident of Minneapolis, county of Hennepin, and State of Minnesota, have invented a new, original, and ornamental Design for a Portable Air Conditioner, of which the following is a specification, reference being had to the accompanying drawing, forming a part thereof, in which Fig. 1 is a three-quarter front perspective view and Fig. 2 is a

view in side elevation of a portable air conditioner showing my new design. The screen shown on the portion of the article in Figs. 1 and 2 is continued throughout the rectangular side area thereof.

I claim:

The ornamental design for a portable air conditioner, substantially as shown and described.

ALLAN A. FEINBERG.
